UNITED STATES PATENT OFFICE.

JULIUS W. FLOWERS AND MINOR J. FOX, OF NEWPORT, OREGON.

PROPELLER.

SPECIFICATION forming part of Letters Patent No. 543,860, dated August 6, 1895.

Application filed August 17, 1894. Serial No. 520,647. (No model.)

To all whom it may concern:

Be it known that we, JULIUS W. FLOWERS and MINOR J. FOX, citizens of the United States, and residents of Newport, in the county of Lincoln and State of Oregon, have invented certain new and useful Improvements in Propellers; and we do hereby declare the following to be a full, clear, and exact description of the invention, such as will enable others skilled in the art to which it appertains to make and use the same.

This invention relates to certain new and useful improvements in propellers, and has for its object, among others, to provide a simple, yet most effective, propeller having revolute flukes or blades for the purpose of reversing the movement of the propeller.

The invention embodies various novel features of construction, all of which tend to produce a better result.

Other objects and advantages of the invention will hereinafter appear, and the novel features thereof will be particularly pointed out in the appended claims.

The invention, in this instance, resides in the peculiarities of construction and in the novel combinations, arrangements, and adaptation of parts, all of them more fully hereinafter described, shown in the drawings, and then particularly pointed out in the accompanying claims.

The invention is clearly illustrated in the accompanying drawings, which, with the numerals marked thereon, form a part of this specification, and in which—

Figure 1 is a side elevation of a propeller and the mechanism therefor embodying the present invention. Fig. 2 is a central longitudinal horizontal section through the device. Fig. 3 is an end elevation of the blades. Fig. 4 is a detail section taken transversely through the hub. Fig. 5 is a sectional view on the line 5 5 of Fig. 1.

Similar numerals of reference are employed to indicate corresponding parts in the several views.

Referring now to the details of the drawings by numerals, 1 designates the main shaft, which is preferably a solid shaft, the inner end of which is designed to be connected with

the engine in any suitable manner. One form of such connection is herein shown, which is seen in Fig. 2, in which 2 represents a squared end of the said shaft, which fits a correspondingly-shaped socket or recess or mortise in 55 the coupling 4, which coupling is connected with the shaft 5, which in turn is connected with the engine. This squared end of the main shaft is designed to have slight endwise movement in the mortise of the coupling. This coupling itself may be of any suitable form of construction. It is shown in Figs. 1 and 2 as composed of the two parts connected by the bolts and nuts 6 in the usual manner. The opposite end of this shaft is 65 screw-threaded, as seen at 7 in Fig. 2, and upon this end of the shaft is threaded the grab 8, as shown in Fig. 2.

9 is a sleeve surrounding the shaft 1, as seen in Fig. 2, which sleeve has a slot 10, extending lengthwise thereof, and in which travels a stud or pin 11, extending from the shaft 1, as seen best in Fig. 2. The head 8 is what we term a "grab," and it has the radial arms 12, which are notched or toothed, 70 as seen in Figs. 1 and 2, to engage notches 13 in the shanks 14 of the blades or flukes 15, as seen in Figs. 1, 2, and 3. These shanks are revolvably mounted in the head or hub 20, which is substantially spherical in shape, and 75 is made in sections which are detachably connected together by means of turn-buttons or analogous devices 21, as seen best in Figs. 1 and 2. These turn-buttons serve also as stops to limit the movement of the shanks of the 80 flukes by engagement with the shoulders 22 thereof, as seen in Fig. 1.

The shaft 1 is designed to have a slight endwise movement by means of the lever 26, pivoted at 27 to a bracket or standard 28, secured 90 upon the base-piece 29, and also having a pivotal connection or joint at 30, while its lower end is forked or bifurcated and at 31 is pivotally connected to the collar 32, which embraces the sleeve 9, engages the pin 11, and 95 is designed to move back and forth on said sleeve. A coiled spring 32^a is arranged between the end of the sleeve 9 and a collar 33^a suitably held on the end of the shaft 1, this spring tending normally to hold the shaft 1 100

inward and keep the grab in engagement with the flukes and prevent revolution of the flukes independent of the other parts.

23 is a sleeve surrounding the sleeve 9, as seen best in Fig. 2, and this sleeve has secured thereto at its outer end a screw-threaded concaved collar or hub 24, within which the shanks of the flukes have a partial bearing, as seen in Fig. 2, these flukes being provided 10 with the notches 13, as above described, upon their diametrically-opposite sides, those upon the one side engaging with the toothed portions 12 of the grab 8, while those upon the other side engage with the notches or teeth 15 25 on the outer face of the hub 24, as seen in Figs. 1 and 2.

The sleeve 23 is provided with a slot 34, which extends circumferentially thereof for a greater or less distance and in which works a 20 pin 35 secured to and projecting from the sleeve 9. The inner end of this tube is toothed or notched, as shown at 36, to form one portion of a clutch, the remaining portion of which will now be described. This remaining portion 37 is mounted to slide upon the tube or sleeve 9 and is provided with the notches 38 to engage with the notches of the part 23, as shown best in Fig. 1, and this movable part of the clutch is adapted to not only 30 slide lengthwise of the tube, but is mounted for partial rotation thereon. It is actuated both in its sliding and rotary movement by means of an arm or lever 39, which is forked, as at 40, to engage the said movable part of 35 the clutch and extends to within convenient reach of the engineer or other attendant. The shanks of the flukes have inner screw-threaded ends 41, extending from base portions 42 resting in recesses in the hub 20, as 40 seen best in Fig. 4, the said widened base portions for base-flanges to produce a bearing-surface for the movement of the flukes or blades and also to strengthen the same. These shanks are engaged by nuts 43, which extend 45 into recesses in the adjacent portions of the hub and are applied to the said shanks through the central opening in the hub to secure the flukes or blades against disconnection, and after the nuts are in position pins may be 50 driven thereinto. Any tendency of the flukes or blades to become disconnected is also obviated by the turn heads or buttons 21, which are fitted in recesses in the hub and have their adjacent ends extending over the adjacent portions of the flanges at the base of the flukes or blades, the said turn buttons or 55 heads being secured by means of the screws 44, as seen clearly in Fig. 4.

In Fig. 5 we have shown the collar 37 as 60 provided with a series of circumferential teeth 45, which are adapted to be engaged by a toothed segment 46 arranged at right angles to and in a vertical plane to a longitudinally disposed operating-lever 39.

65 In operation the shaft 1 when moved lon-

gitudinally against the action of the spring 32 throws the grab 8 outward and disengages the toothed spider-arms thereof from the teeth in the flukes or blades 15. The clutch connection is then manipulated to engage the 70 clutch, when the collar or movable part 37 thereof is partially rotated to oscillate the hub and the flukes or blades carried thereby, which, it will be understood, are now in engagement with the segmental teeth on the 75 head 24, and through the oscillating movement thus obtained the said flukes or blades will be turned in a plane at right angles to the head.

Having thus described the invention, what 80 is claimed as new is—

1. In a propeller, the combination with the main shaft and a toothed grab secured to one end thereof, of a hub mounted on the end of said shaft, revoluble flukes or blades rotatably mounted on the hub and adapted to be held against movement by engagement with the toothed arms of said grab, means for moving said shaft lengthwise relatively to said hub for disengaging said grab from said 90 flukes, and means for rotating said flukes, substantially as and for the purpose described.

2. In a propeller, the combination with the main shaft and a toothed grab secured to one 95 end thereof, of a hub mounted on the end of said shaft, revoluble flukes or blades rotatably mounted on the hub and having teeth on opposite sides thereof, one set of which teeth are engaged by said toothed grab, a 100 collar mounted for limited rotation on said shaft, a flanged head secured to said collar and provided with teeth which are adapted to engage teeth on the opposite side of said flukes, means for moving said shaft lengthwise relatively to said hub for disengaging 105 said grab from said flukes, and means for rotating said collar, whereby said flukes are turned on their axes, substantially as and for the purpose described.

3. In a propeller, the combination with the main shaft and a toothed grab secured to one end thereof, of a hub mounted on the end of said shaft, revoluble flukes or blades rotatably mounted on the said hub having teeth 115 on opposite sides thereof, one set of which is engaged by the toothed arms of said grab, a fixed sleeve surrounding said shaft having a longitudinal slot therein through which passes a pin secured to said shaft, a collar 120 surrounding said sleeve and adapted to engage said pin, a lever pivoted to said collar and fulcrumed in a suitable standard or support, whereby said shaft may be moved lengthwise relatively to said hub, a second 125 sleeve mounted for limited rotary movement on said first sleeve, and provided with notches at its rear end, a flanged head secured to said sleeve and having teeth which are adapted to engage the other set of teeth on said flukes, 130

a clutch having teeth adapted to engage the notches in said sleeve, means for throwing said clutch into and out of engagement with said sleeve, and afterward rotating the same, substantially as and for the purpose described.

In testimony whereof we have signed this

specification in the presence of two subscribing witnesses.
